UNITED STATES PATENT OFFICE.

ELZA L. WALTERS, OF ANDERSON, INDIANA.

CARBURETOR.

Application filed April 11, 1919. Serial No. 289,226.

To all whom it may concern:

Be it known that I, ELZA L. WALTERS, a citizen of the United States, residing at Anderson, in the county of Madison and State of Indiana, have invented certain new and useful Improvements in Carburetors, of which the following is a specification.

The invention has relation to carburetors for use in connection with internal combustion engines for creating a mixture of air and fuel which is utilized as the fuel medium for operating this type of engines.

The invention aims to provide a carburetor embodying a relatively small number of parts and which when adjusted operates automatically at low, high or any intermediate speed, the valves automatically adapting themselves to the varying speeds so as to produce a mixture of air and fuel 20 which insures a nearly perfect combustion, thereby preventing the accumulation of carbon.

The drawings illustrate a preferred embodiment of the invention. However, it is to be understood that in adapting the same to meet different conditions, various changes in the form, proportion, and minor details of construction may be resorted to without departing from the nature of the invention 30 as claimed hereinafter.

Referring to the accompanying drawings which illustrate a carburetor embodying the invention,

Figure 1 is a horizontal section through the mixing tube, the float chamber being shown in plan.

Figure 2 is an end elevation, the float chamber being shown in section.

Figure 3 is an end elevation of the mixing tube partly broken away to show the stop for limiting the movement of the throttle.

Fig. 4 is a section of the float and parts associated therewith on the line 4-4 of Fig. 2, the chamber being omitted.

Fig. 5 is an end elevation of the fuel valve, and

Fig. 6 is a section on the line 6-6 of Fig. 5.

Corresponding and like parts are referred to in the following description and indicated in the several views of the drawings by like reference characters.

The carburetor comprises essentially a

float chamber 1 and a mixing tube 2 which are connected in any suitable manner as 55 by casting or by a bracket 3.

The float chamber 1 is closed at its top by means of a cover 4 in which is formed a threaded opening to receive the reduced externally threaded end of a tube 5. Slots 6 60 are formed in opposite sides of the inner or lower end of the tube 5 to receive a bar 7 which projects beyond opposite sides of the tube to engage a float 8. The center portion of the bar 7 is widened and apertured 65 to receive the lower pointed end of a valve 9 which controls the flow of the liquid fuel through the tube 5 into the float chamber. A valve seat 10 is formed at the inner end of the reduced portion of the tube 5 and the valve 9 closes upwardly thereagainst, the upper end of the valve being pointed to enter the reduced portion of the tube 5 and the shoulder formed at the base of the reduced end constituting the valve proper 75

which closes on the seat 10. The tube 5 remains fixed after being adjusted, but the float 8 and valve 9 are movable and are controlled in their movements by the change of level of the fuel in the chamber 1. A pin 80 11 supported in the lower end of the tube 5 has its end portions projecting to engage the float 8 and limit the downward movement of the float and the valve 9. The float 8 is freely movable on the tube 5 and the 85 opening through which the tube 5 passes is provided with a metal lining or sleeve 12. The end portions of the bar 7 pass through the lining 12 and float 8, thereby serving to retain the lining or sleeve 12 in position. 90 The metal lining 12 prevents any binding of the float on the tube 5. A thimble or coupling 13 is fitted in an opening formed in the bottom of the float chamber 1 and constitutes an outlet for the fuel. A pipe 95 14 connects with the coupling or thimble 13 and conveys the fuel from the float chamber to the mixing tube.

A pin 15 is loosely mounted on the cover 4 and enables the carburetor to be primed 100 when the valve 10 is unseated by the engagement of the pin 15 with the float 8. While the valve 10 is kept open, fuel will continue to flow into the chamber through the tube 5, consequently raising the level of 105 the fuel in the mixing chamber, the over-

flow being used for priming purposes. A lever 16 is pivotally mounted upon the bracket 17, which bracket is secured to the projecting end of the tube 5 by means of a nut 18. This nut 18 also acts as a binder to secure the tube 5 in adjusted position in the chamber 1. The lever 16 has one of its ends cooperating with the pin 15 and its other end is connected in any desired form, so as to be operated from the dash board, steering wheel or any other part of the vehicle.

The mixing tube 2 is provided at one end with a throttle 19 of the usual butterfly type which has a slot adjacent one edge to permit idling or for constant slow speed and is adapted to be operated by the usual control lever in a manner well understood. A set screw 20 is threaded into the side of the mixing tube 2 and may be adjusted to limit the movement of the throttle 19. A bushing 21 is threaded into the opposite end of the mixing tube 2 and adjustably receives a valve seat 22 which is connected thereto by means of cooperating screw threads to permit adjustment of the valve seat 22 so as to enable the air valve 23 to be seated thereon with greater or less facility as may be required.

An air tube 24 is disposed centrally of the mixing tube 2 and is supported by means of a bridge 25 and a fuel nozzle 30 extending therethrough. The valve 23 is movable on the air tube 24 and is normally held seated by means of an expansible helical spring 26 which is confined between the bridge 25 and the valve 23. The tension of the spring 26 may be regulated by adjustment of the bridge 25 by rods 27 which are connected at one of their ends to the bridge 25 and the other ends threaded and passing through the bushing 21. Nuts 28 are secured to the threaded end of the rods 27 to hold the bridge in adjusted position. Locking elements 29 may be used to hold the nuts 28 in position by wedging said elements 29 between the nuts 28 and the valve seat 22 as shown in Figure 2.

A fuel nozzle 30 extends through a side of the mixing tube 2 and a side of the air tube 24 and has its inner end terminating in an outlet 31 within the air tube 24. A small diagonal opening 31' is provided at the rear of the outlet to act as an additional vent for the fuel nozzle 30, said fuel nozzle having its outer end connected to the pipe 14 to receive the fuel from the chamber 1. A needle valve 32 is connected to the air valve 23 to move therewith by a U-shaped rod 33 which is adjustable on the air valve 23 so as to regulate the fuel outlet for idling or for constant low speed. The valve 32 is mounted at the closed end of the U-shaped rod 33 the free ends of said rod being threaded and passing through the bridge 25 and the valve

23. Nuts 34 are secured to the threaded ends of the rod 33 to adjust said rod on said valve 23. Brackets 35 secured to the inner walls of the mixing tube 2 act as guiding means in conjunction with the bridge 25 for the rod 33.

A fuel pipe, not shown, is adapted to be coupled with the projecting end of the tube 5 while the mixing tube 2 is adapted to be connected in any suitable manner to the intake manifold of the engine. It is apparent that the several parts may be properly adjusted by setting the tube 5, valve seat 22 and fuel valve 32. The valve seat 22 may be adjusted by turning it upon the bushing 21 whereby the air valve 23 and needle valve 32 are moved accordingly. If it is desired to further adjust the needle valve 32 without moving the air valve 23, so as to permit a slow feeding of fuel therethrough for idling, said adjustment may be made on the rod 33 by the nuts 34. If it is desired to increase the tension of the spring 26 on the valve 23, the bridge 25 is moved forward by tightening the nuts 28 on the rods 27.

When the engine is running at low speed air enters the tube 24 and mixes with the fuel drawn from the outlet 31. As the speed of the engine increases the increased suction unseats the air valve 23 more or less, thereby admitting of a greater volume of air being drawn into the mixing tube. The unseating of the air valve 23 effects proportionate opening of the valve 32, whereby more fuel is supplied to mix with the greater volume of air. This action is automatic as will be readily understood. The float 8 in the chamber 1 maintains a predetermined level of fuel in the float chamber and the level of the fuel in the outlet 31 corresponds with the level of the fuel in the chamber 1, the parts being so adjusted that the level of the fuel in the outlet 31 is such as to prevent fluting of the carburetor while at the same time assuring proper and ample supply of fuel when the engine is running at low speed and when starting. Should the float 8 or valve 9 stick, the same may be moved by operating the priming lever 16 in a manner well understood.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claim.

Having thus fully described my invention, what I claim as new and desire to secure by Letters Patent is:—

In a carburetor, a mixing tube having an air opening, an air tube, means for supplying fuel to the air tube, a fuel regulating

valve, a valve seat adjustable in the air opening, an air valve seated on the valve seat and mounted on the air tube, an expandible helical spring mounted on the air tube and holding the air valve seated, a bridge for supporting the air tube and engaging one end of the spring, means for adjusting the bridge to vary the tension of the spring and means adjustably connecting the air and fuel

valves and adapted to be guided in its movement by said bridge.

In testimony whereof I affix my signature in presence of two witnesses.

ELZA L. WALTERS.
